Walter P. Newhall, Inventor
J. S. Barrett, Secy. of the U. S. Patent Office
W. H. May

UNITED STATES PATENT OFFICE.

WALTER P. NEWHALL, OF NEW YORK, N. Y.

IMPROVEMENT IN UMBRELLAS.

Specification forming part of Letters Patent No. 38,325, dated April 28, 1863.

To all whom it may concern:

Be it known that I, WALTER POWERS NEWHALL, of the city, county, and State of New York, have invented certain new and useful improvements in forming the eyes in metal bows of umbrellas and parasols for attaching the braces thereto; and I do hereby declare the following to be a full description of the same.

The nature of my invention consists in forming the eye from the solid wire by bending it by means of a press and die so as to form a loop, and then soldering the shanks together, so as to make a continuous bow, and at the same time a solid and durable eye to attach the brace of the umbrella thereto; but to describe my invention more particularly, I will refer to the accompanying drawings, forming a part of this specification, the same letters of reference wherever they occur referring to like parts.

Figure 1 represents a steel-metal umbrella-bow, having a brace attached thereto. Fig. 2 represents the bow.

Letter *a* is the steel bow of an umbrella-frame. At the middle of it a loop or eye, *b*, is formed. This is done by bending the bow in a suitable press and die, so as to form the loop and restore the continuous line of the bow. The form of the loop is somewhat of a U shape, but having the ends of it converg-

ing toward each other, so as to form the eye. These ends are united together by soldering *c*. By this means the entire strength and elasticity of the bow is preserved, while at the same time a cheaper, more simple, and durable eye is formed than could be made by any other means known of.

Letter *d* is a brace, and *e* the pin for connecting it with the bow.

It will be obvious that in heavy umbrella steel-bows the loop may be formed and used without soldering the ends together, as the strength of the bow would be sufficient to sustain the umbrella. I, therefore, do not desire to limit my invention so as to be compelled to solder the ends of the loops in all cases.

Having now described my invention, I will proceed to set forth what I claim, and desire to secure by Letters Patent of the United States—

An umbrella, its rod or bow having the eye or loop, for attaching the brace thereto, formed from the continuous length of the said rod or bow, by bending it in the shape substantially as hereinbefore described.

WALTER P. NEWHALL.
